Primary Examiner — Selina Sikder

(57) **CLAIM**

The ornamental design of an electrical switch housing unit, as shown and described.

DESCRIPTION

FIG. 1 is a front perspective view of an electrical switch housing unit;

FIG. 2 is a rear perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top elevation view thereof; and,

FIG. 8 is a bottom elevation view thereof.
